UNITED STATES PATENT OFFICE.

SIDNEY ROSENSTEIN. OF NEW YORK, N. Y.

RENEWABLE MATCH BOOK.

Application filed March 18, 1925. Serial No. 16,458.

To all whom it may concern:

Be it known that I, SIDNEY ROSENSTEIN, a citizen of the United States, and a resident of the city of New York, borough of 5 Manhattan, in the county and State of New York, have invented a new and Improved Renewable Match Book, of which the following is a full, clear, and exact description.

10 This invention relates to renewable match books, an object of the invention being to provide a match book including a cover which may be of any suitable material, which may be ornamented in any desired 15 manner, and which functions as an enclosure for a renewable strip of matches.

This invention has to do particularly with that type of matches known on the market as "book matches", which are made from a 20 strip or strips of paper, and it is the primary object of my invention to provide for such a strip of matches a cover which may be rendered individual and artistic so that it may be repeatedly used for strips of 25 matches, the latter being removed from the cover and replaced as occasion may require.

With these and other objects in view, the invention consists in certain novel features of construction and combinations and arrangement of parts, which will be more 30 fully hereinafter described and pointed out in the claim.

In the accompanying drawings—

Figure 1 is a view in elevation, showing 35 my improved match book in closed position;

Figure 2 is a similar view, showing the cover of the match book open;

Figure 3 is an exaggerated view in longitudinal section on the line 3—3 of Figure 1;

40 Figure 4 is a view of the match strip or refill removed from the cover.

1 represents the cover of my improved match book. This cover may be made of paper, leather, or any other suitable material. It is made of the proper length and width and has two folds, namely, a fold 2 adjacent one end of the strip, and a fold 3 at a point removed from the other end of the strip.

45 For purposes of illustration I shall refer to the portions of the cover between the fold lines as follows: that portion between the fold line 2 and the end of the strip constituting the front flap 4; the other end of the 50 cover between the fold 3 and the end of the

cover constituting a covering flap 5; and the intermediate portion of the strip constituting a back 6.

7 represents a strip of matches, preferably of the ordinary paper type, connected at one end by an uncut portion such as is common in the art. Over this uncut portion of the match strip I locate a narrow sheet 8 containing a surface 9 on which the matches are to be struck. This sheet 8 is secured to the match strip 7 by an eyelet 10. This eyelet is adapted to register with openings in the front flap 4 and in the back 6 of the cover 1 to receive a fastener 11 which may constitute a small bendable fastener of 70 the well known Gill type.

It will be noted that the sheet 8 is wider than the front flap 4 so that the striking surface 9 is exposed and the matches when torn from the strip 7 can be readily rubbed 75 against the surface 9 to ignite them.

When a match strip is entirely used up or partially used up, the fastener 11 can be withdrawn and a new strip of matches inserted in the cover so that the device as a 80 whole will present a neat and attractive appearance and be ready for further use.

By reason of this construction I am enabled to provide individual or ornamental covers which may be used over and over 85 again in connection with any desired number of refills to suit the trade.

Various slight changes and alterations might be made in the general form of the parts described without departing from my 90 invention and hence I do not limit myself to the precise details set forth but consider myself at liberty to make such slight changes and alterations as fairly fall within the spirit and scope of the appended 95 claim.

I claim:

A match book, comprising a strip of folded material, said strip having two fold lines whereby when the strip is folded the intermediate portion of the strip constitutes a back member and the two end portions front members, one of said front members being appreciably shorter than the other and the longer front member constituting a covering member, a strip of matches located between the back member and the shorter front member, a strip having match striking material thereon located in front of the strip 100 of matches and between the shorter front 105 member and the front member being appreciably shorter than the other and the longer front member constituting a covering member, a strip of matches located between the back member and the shorter front member, a strip having match striking material thereon located in front of the strip 110 of matches and between the shorter front

member and the strip of matches and extending above the end of the shorter front member, said covering member adapted to be interposed between the match striking strip and the shorter covering member to enclose the matches and match striking strip, said back portion, said shorter front

portion, said match strip, and said match striking strip having aligned openings and a designedly removable fastener projected ¹⁰ through said opening and securing the parts together.

SIDNEY ROSENSTEIN.
